United States Patent Office

Des. 222,167

Patented Oct. 5, 1971

222,167

PLATE OR SIMILAR ARTICLE

Ryotaro Takeoka, Aichiken, Japan, assignor to Noritake Co., Inc., New York, N.Y.

Filed May 6, 1970, Ser. No. 22,848

Term of patent 7 years

Int. Cl. D7—01

U.S. Cl. D44—15

The figure is a plan view of a plate or similar article showing my new design.

The plate is of a conventional configuration when viewed from the side and bottom thereof.

I claim:

The ornamental design for a plate or similar article, substantially as shown and described.
